LETTER OPENER OR THE LIKE

Clayton A. Laughlin, Minneapolis, Minn., assignor to Arthur Salm Inc., Chicago, Ill., a corporation of Illinois

Filed Apr. 25, 1967, Ser. No. 6,832

Term of patent 14 years

Int. Cl. D19—02

U.S. Cl. D74—10

FIG. 1 is a plan view of one face of a letter opener incorporating my new design, the other face thereof being substantially identical;

FIG. 2 is a side view of the letter opener of FIG. 1, the opposite side thereof being substantially identical;

FIG. 3 is an end view of the letter opener of FIG. 1; and

FIG. 4 is a sectional view of the letter opener of FIG. 1, taken on the line 4—4 of FIG. 2.

The dominant features of my design reside in the particular handle portion which is ornamented as shown, the blade portion being included for illustrative purposes only to complete the article.

I claim:

The ornamental design for a letter opener or the like, substantially as shown and described.
